TUNING INDICATOR TUBE

Harry C. Thompson, Montclair, N. J., assignor
to Radio Corporation of America, a corpora-
tion of Delaware

Original application June 27, 1935, Serial No.
28,665. Divided and this application May 19,
1936, Serial No. 80,474

4 Claims. (Cl. 250—27.5)

My invention relates to electron discharge de-
vices, more particularly to such devices useful
as visual indicators of voltage and having a flu-
orescent electrode which is rendered luminous,
5 and has the appearance of a pattern of light
which may be of constant height or length and
varying width and which changes in response to
the change in the magnitude of the applied volt-
age, a device of this character being particularly
10 useful as a tuning indicator in radio receiving
sets.

This application is a division of application No.
28,665, now Patent No. 2,051,188, issued August
18, 1936, filed June 27, 1935 and assigned to the
15 same assignee as the present application.

It is an object of my invention to provide an
improved electron discharge device of the kind
described, which is particularly suitable for use
as a visual tuning indicator in a radio receiving
20 set and in which resonance is indicated by a bri-
lliant luminous glow on an electrode.

In general my invention comprises an envelope
having within it a straight thermionic cathode
having two separate electron emitting sections
25 around one of which are positioned at least one
grid and an anode. Around the other section are
mounted the visual tuning indicator elements
comprising preferably a straight control elec-
trode parallel to the cathode, and an anode which
30 may be flat or cylindrical and may be of sheet or
of mesh material and coated with material which
fluoresces in response to electron bombardment.
In operation the electrons flow from the cathode
35 to the anode with sufficient velocity to bombard
the plate and render it luminous. The control
electrode is electrically connected to the anode
surrounding the grid and the elements of the
tube are so connected in a radio receiving circuit
40 that when the circuit is tuned to resonance with
an incoming signal the luminous portion of the
indicator anode is of a predetermined size. In
one form of the device the connection is such that
the luminous portion of the anode is of a maxi-
45 mum width and hence the dark space of mini-
mum width when the circuit is tuned to reso-
nance, the height or length remaining constant.

The novel features which I believe to be char-
acteristic of my invention are set forth with par-
ticularity in the appended claims, but the inven-
50 tion itself will best be understood by reference
to the following description taken in connection
with the accompanying drawing in which Figure
1 shows an electron discharge device embodying
my invention with parts broken away to show
55 details of construction; Figure 2 is an enlarged

top and side view showing details of construction
of the voltage indicating elements of the tube
shown in Figure 1; Figure 3 shows a circuit ar-
rangement using a tube made in accordance with
my invention; and Figures 4 and 5 are top views
5 of further modifications of the tuning indicator
elements of the electron discharge device shown
in Figure 1.

The electron discharge device or tuning indi-
cator tube shown in Figure 1 comprises an evac-
uated envelope 10 provided with the usual stem
and press 11, and base 12. Supported from the
press are a cathode 13, preferably the conven-
tional indirectly heated equipotential type, a grid
14 and anode 15 surrounding the cathode. 10

In accordance with my invention I mount in
the dome portion of the envelope 10 the visual
indicating portion of the tube comprising a cath-
ode, a control electrode and an anode having
preferably a flat surface presented to said cath-
ode and control electrode and provided with a
20 coating which fluoresces when subjected to elec-
tron bombardment. While the anode having the
fluorescent coating may be of the mesh type and
viewed from either side and might have flat or
25 curved surfaces, I may make it of flat or curved
sheet material and coat only one side, which may
be directly viewed.

As shown in Figures 1 and 2 the cathode 13 is
extended into the dome portion of the envelope 30
as shown at 16 and has a second emitting sec-
tion 16' for applying the electrons in the visual
indicating device. A control electrode 25 in the
form of a cylinder provided with a longitudinal
opening 26 through which electrons pass from 35
the cathode emitting portion 16' to the flat coated
anode 27 surrounds the cathode and is sup-
ported from a cross bar 18 electrically connected
to the side rods 19 of the anode 15. This control
electrode determines the pattern of the lumines- 40
cent portion of the anode 27, which is shown as
made of sheet material and coated with any con-
ventional luminescent material, and is supported
by rods 21' extending from the press 11.

In operation the voltage on the anode 15 is 45
applied to the control electrode 25, the voltage
on this electrode determining the width of the
pattern of light on the anode 27, the height of the
pattern of light being constant and equal to the
height of the anode. The less negative this con-
50 trol electrode 25 is biased with respect to the
anode 27 the wider will be the luminescent area
(b) on the anode 27 inasmuch as the beam of
electrons from the cathode becomes less sharply
55 focused than when the negative bias on the con-

trol electrode is large and the luminescent area (a) is narrower. In this embodiment of my invention the luminescent portion of the voltage or tuning indicator may be viewed from the side of the tube with ease. The emitting area 16' of the cathode 16 is confined as shown to prevent the control electrode 25 drawing any substantial amount of current.

Referring to Figure 2, which shows a top view of the tuning indicator portion of the invention shown in Figure 1, the beam control electrode 25 is so biased that when no signal is being received the voltage difference between the control electrode 25 and the anode 27 is such that only the portion a of the anode is luminescent. As the set is tuned to resonance the voltage difference between the anode 27 and the electrode 25 becomes less, so that the control effect of the electrode 25 on the electrons leaving the cathode 16 is less, permitting electrons from the cathode 16 to reach more of the anode 27 so that when the set is tuned to resonance the anode is luminous over the surface as shown by lines b.

The application of an electron discharge device made in accordance with my invention to a radio circuit is shown in Figure 3. Normally the anode 15 of the triode section of the tube is electrically connected through a resistor 40, to a source of voltage 41. The indicator anode 30 is connected directly to the source of voltage 41. With no voltage on the grid 14 a certain predetermined amount of current flow through the triode section of the tube causes a drop in resistor 40, so that the voltages applied to anode 15 and indicator anode 27 have the greatest differential, the voltage on anode 15 being at the lower potential. The voltage on anode 27 does not change while that on the anode 15 decreases, due to the drop through resistor 40. This makes the control electrode 25 negative with respect to anode 27, thus reducing the width of the luminescent portion of the anode 27. As the voltage on the control grid 14 increases in the negative direction the current flow to the anode 15 decreases so that the voltage drop through the resistor 40 decreases. Under these circumstances the voltage differential between anode 15 and indicating anode 27 decreases so that the control electrode 25 becomes less negative with respect to the anode 27. This permits the width of the luminescent portion to increase. Thus the luminescent portion increases as the negative bias on the control grid 14 increases. This characteristic of the tuning indicator tube is made use of when connected to a conventional automatic volume control circuit. The rectifier tube 42 has an anode 43 connected to one side of the radio frequency or intermediate frequency transformer 44 coupled to the receiving circuit not shown, and a cathode 45 connected through a grid leak 46 and by-pass condenser 47 to the other side of the transformer 44. The cathode side of the transformer 44 is connected through resistor 48 to control grid 14 of the tuning indicator tube. A radio frequency by-passing condenser 49 connects the grid to ground, and the conductor 50 may be connected to other parts of the circuit to provide automatic volume control. As the receiving circuit is tuned to resonance and rectification takes place through the tube 42, the cathode side of the radio frequency transformer becomes negative with respect to ground due to the current through resistor 46. This negative voltage is applied to the control grid 14 as a negative bias with the result that

the current through the triode portion of the tube is reduced, thus causing the width of the luminescent portion of the tuning indicator anode 27 to increase as explained above. In this arrangement the control electrode is positive with respect to the cathode. Several advantages follow from this arrangement over that in which the control electrode is biased negatively with respect to the cathode. The boundaries of the electron beams are sharp and well defined. There can be a high concentration of electrons at the edges of the luminous areas so that the luminosity is uniform. The high current to the luminescent portion of the screen can be obtained at low voltages and hence a high luminosity is the result. A positive control electrode is suitable for direct coupling to an amplifier, that is it may be directly connected to the plate of an amplifier tube as shown in Figure 1 for example. Furthermore, a tube made in accordance with my invention is not critical to variations in cathode temperatures and is susceptible for use with alternating and direct voltages and currents.

In Figure 4 the control electrode 30 is a V-shaped member on one side of the electron emitting cathode 16 and the luminescent anode is similarly shaped with the coating on the side facing the cathode. Figure 5 shows an arrangement very similar to that shown in Figure 4 except that the control electrodes 35 and anode 36 are flat.

In the embodiment shown in Figures 4 and 5 the control electrodes 30 and 35 may be connected to the grid of the triode section, so that they are biased negatively with respect to the cathode. With this connection the luminescent portions between the lines a and b in Figures 4 and 5 indicate the luminescent portions when the circuit in which the tube is used is tuned and untuned to an incoming signal.

While I have indicated the preferred embodiment of my invention of which I am now aware and have also indicated only one specific application for which my invention may be employed, it will be apparent that my invention is by no means limited to the exact forms illustrated or the use indicated, but that many variations may be made in the particular structure used and the purpose for which it is employed without departing from the scope of my invention as set forth in the appended claims.

What I claim as new is:

1. An electron discharge device having an envelope enclosing a straight thermionic electron emitting cathode, an anode having a flat surface adjacent said cathode and having a fluorescent coating thereon, a control electrode comprising a pair of straight conductors parallel to and on the opposite side of the cathode from said anode for determining the extent of the anode reached by the electrons emitted by the cathode.

2. An electron discharge device having an envelope, a cathode within the envelope having a plurality of electron emitting surfaces along its surface, a grid and anode surrounding one of said electron emitting surfaces and a fluorescent anode having a flat surface adjacent another of the electron emitting surfaces of said cathode and a control electrode positioned on the opposite side of the cathode from said fluorescent anode and comprising a conductor parallel to the cathode and connected to the anode surrounding the grid for producing on said fluorescent anode a beam of substantially constant length and of a width depending upon the voltage applied to

said control electrode through the anode around the grid.

3. An electron discharge device having an envelope, a straight thermionic cathode within said envelope for emitting electrons, a V-shaped anode adjacent the cathode and coextensive therewith and coated with a material which fluoresces when struck by electrons from said cathode and a control electrode comprising a V-shaped member 10 on the other side of said cathode from said anode and coextensive with said cathode and anode, the width of the luminescent portion of the anode struck by said electrons being dependent on the voltage applied to said control electrode.

4. An electron discharge device comprising a cathode having two separate emitting sections, a grid and anode surrounding one of said electron emitting sections, an anode having a flat surface adjacent the other of said emitting sections and coated with a fluorescent material, and a control electrode parallel to and on the other side of the other emitting section of said cathode from the anode coated with luminescent material and electrically connected to and supported by the anode surrounding said grid. 10
